CLAIM

The ornamental design for a lid of barbecue stove, as shown and described.

DESCRIPTION

FIG. 1 is a perspective view of a lid of barbecue stove showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof showing the design in use with a barbecue stove.

The broken lines depict environment and form no part of the claimed design.
